United States Patent Office

Des. 186,781
Patented Dec. 1, 1959

186,781

BRACELET LINK OR SIMILAR ARTICLE

Murray Lawrence Cowan, Boston, Mass., assignor to Speidel Corporation, Providence, R.I., a corporation of Rhode Island

Application July 14, 1959, Serial No. 56,766

Term of patent 14 years

(Cl. D45—4)

FIG. 1

FIG. 2

FIG. 4

Fig. 1 is a top plan view of a bracelet link or similar article showing the new design;

Fig. 2 is a side elevational view looking from bottom to top at the link shown in Fig. 1;

Fig. 3 is an enlarged side elevational view looking from right to left at the link shown in Fig. 1 with the conventional bottom surface thereof being shown in broken lines; and

Fig. 4 is an enlarged side elevational view looking from left to right at the link shown in Fig. 1 with the conventional bottom surface thereof being shown in broken lines.

I claim:

The ornamental design for a bracelet link or similar article, substantially as shown and described.
